UNITED STATES PATENT OFFICE.

ROBERT D. WEBB, OF MINDEN, LOUISIANA.

HOUSING FOR HIGH-DENSITY COMPRESSES.

Application filed July 20, 1925. Serial No. 44,860.

The present invention relates to presses and particularly to cotton presses of the high density type, such as disclosed in Patent No. 828,002, issued August 7, 1906 to 5 Samuel J. Webb.

High density cotton presses such as disclosed in the patent just referred to comprise essentially upper and lower main platens for effecting the actual compression 10 of the cotton and side plates for holding the cotton fibers against lateral displacement while such compression is being effected. The resulting bale is of small size and very dense. The side plates are hinged about 15 their lower edges and adapted to be swung from their operative positions, in which they lie parallel to each other and in vertical planes, to their inoperative positions, in which they lie substantially in the same 20 horizontal plane, so that the removal of a bale and placement of an uncompressed or plantation bale in the press are readily effected. The movement of the side plates, which are hinged about their lower edges, 25 from operative to inoperative position and vice versa, is effected by mechanism which includes a power operated toggle for each side plate, the upper end of which is pivoted to the side plate and the lower 30 end of which is pivoted upon a heel pin or rod supported from the frame or housing of the press. While the press is 35 in operation, and compressing a bale, the toggles must withstand great pressure, as will be evident, and hence the heel pins must be very substantially supported from the frame.

My invention relates to the supporting mechanism for these heel pins, and its object is to provide such mechanism which is of a rigid construction forming a strong support, while at the same time permitting adjustment of its members so that the positions of the heel pins may be slightly modified or changed from time to time to insure the easy and proper adjustment of the toggles that move the side plates or displacement plates of the press, permitting adjustment for wear of parts, such as the toggle 45 joints and heel pins and heel pin bearings.

The invention is applicable to presses heretofore constructed for use as well as presses hereafter to be newly constructed, and, when applied to presses which have been heretofore manufactured and sold, greatly increases their effectiveness in operation and

operative value, as well as greatly increasing the length of life.

One form of the invention is illustrated in the accompanying drawings in which 60

Figure 1 is a front elevation of a high density compress, showing the invention incorporated therein;

Figure 2 is a side elevation of the same; 65

Figure 3 is a perspective view of a detail; and

Figure 4 is a vertical section of a modification showing this detail integral with the housing.

The compress in its entirety, with the exception of the present improvement, is disclosed in the prior patent to Samuel J. Webb above mentioned, and will not be described in detail herein. Briefly stated it is provided with a stationary upper platen 10 and movable lower platen, which is not perceptible in the views of the present application, a power piston in an elevated cylinder 11 for bringing these platens together and separating them, and side plates or displacing 70 plates 12, which are movable from the positions in which they are indicated in full lines in Figure 1 to the positions in which they are shown in dotted lines in the same figure by mechanism now to be described. 75

Each displacement plate is provided with a toggle comprising a member 13 and a member 14 pivoted together at 15, for operating the same. The inner end of each member 13 of each toggle is rounded and fits 80 within a cylindrical groove or socket 16 in the corresponding displacement plate, and the outer end of each toggle member 14 is journaled upon a heel pin 17.

Heel pins 17 are parallel to each other and 95 supported by tie rods from the housing of the compress. Thus parallel horizontal tie rods 18 secured by brackets or clamping members 19 are provided with apertured ends thru which the heel pins extend. These 100 tie rods 18 hold the heel pins against horizontal movement outwardly when pressure is exerted against the displacement plates 16.

On each side of the machine are disposed 105 two inclined tie rods 20, the lower ends of which are enlarged and apertured to receive the heel pins 17 and the upper ends of which lie in grooves 21 in brackets 22. These brackets may be either integral with the frame members 23 of the press, or formed 110 separately and bolted thereto. In the preferred embodiment of the invention herein

disclosed, these brackets are bolted to the frame members 23. In Figures 2, 3 and 4, the details of the brackets are clearly disclosed. Each bracket is provided at its upper end with an aperture 24 for a bolt 25 horizontally disposed, which bolt passes thru the frame members 23 and has its end threaded for a nut 26. These bolts, therefore, serve not only as braces for the frame members 23, but also serve to securely fasten the upper ends of brackets 22 to the frame members.

The back plate of each bracket is provided with an additional series of apertures 27 for bolts 28, provided as additional securing means. Each bracket has a foot plate 29 which meets its back plate 30 at an angle of ninety degrees. Perpendicular webs 31, arranged at right angles to the back plate, connect the back and foot plates, and on one of these on each bracket is arranged the yoke member 32 having the groove 21 previously referred to. The upper surface 33 of this grooved member is disposed in a plane which is at right angles to the tie rod 20 when the structure is assembled and serves as a seat for a ring or washer 34 which encircles the upper end of each tie rod. Above the washers 34 are adjusting nuts 35 which are threaded upon the upper ends of the tie rods. By adjusting these nuts, it will be seen that the heel pins 17 may be drawn parallel or lowered or raised to a slight extent to secure the exact adjustment of the heel pins which may be desired. From time to time, in the operation of the machine, it will be desirable to effect these adjustments; and the construction just described also facilitates assembly of newly constructed presses.

In the form of the invention shown in Figure 4 the bracket is integral with the frame of the compress. This is the construction preferable in the case of compresses hereafter to be constructed. Those already in use may be fitted with the improved bracket shown in Figures 1, 2 and 3.

Having thus described the invention what is claimed as new and desired to be secured by Letters Patent is:

1. The combination with a high density compress having a housing, upper and lower platens, hinged side plates, and toggles for operating the side plates, of parallel heel pins for the toggles, and a frame for supporting the heel pins so as to be vertically adjustable for the purpose set forth, said frame including inclined tie rods having

their upper ends threaded and their lower ends engaging the heel pins, seating surfaces on the outer sides of the housing transverse to the tie rods respectively and nuts on the upper ends of said tie rods which bear against said seating surfaces for the purpose set forth.

2. The combination with a high density compress having a housing and a pair of heel pins, of a pair of tie rods attached at one end to said heel pins, and a bracket on each side of said housing, to receive the other ends of said tie rods, an abutment on each bracket, and means cooperating with each tie rod for transmitting pressure from said heel pin to said abutment, said means being adjustable to vary the length of said rod.

3. The combination with a high density compress having a housing and a pair of heel pins, of a pair of tie rods attached at one end to said heel pins, and a bracket on each side of said housing having a recess forming a seating surface for the other end of each tie rod, means on each tie rod for adjusting the position of its associated heel pin, each of said recesses being open at its outer side to facilitate assembly, replacement and adjustment of said press.

4. The combination with the housing of a high density compress of brackets on the outer sides thereof provided with openings for the reception respectively of downwardly and outwardly inclined tie rods, the brackets having inclined bearing surfaces constituting seating surfaces for nuts threaded upon the respective tie rods.

5. The combination set forth in claim 4, in which the openings comprise grooves with their long axes downwardly and outwardly inclined and parallel to the respective tie rods.

6. The combination with a high density compress having a housing, upper and lower platens, hinged side plates, and toggles for operating the side plates, of parallel heel pins for the toggles, and a frame for supporting the heel pins so as to be vertically adjustable, said frame including inclined tie rods having their lower ends engaging the heel pins, means on said housing to receive the upper end of said tie rods, and means cooperating with said first named means for adjusting the length of said tie rods to take up wear in the operating parts, and preserve the operative position of said side plates.

In testimony whereof I hereunto affix my signature.

ROBERT D. WEBB.
